(57) **CLAIM**

The ornamental design for a shoe outsole with a surface ornamentation contrast, as shown and described.

DESCRIPTION

FIG. 1 is a front perspective view of a shoe outsole with a surface ornamentation contrast showing our new design; FIG. 2 is a plan view thereof; and, FIG. 3 is a rear perspective view thereof.

The broken lines showing the remainder of the shoe are for environmental purposes only and form no part of the claimed design. The contrast in grayscale shading between the different regions in the figures represents a contrast of appearance.
